Charles L. Wright.

UNITED STATES PATENT OFFICE.

MAXWELL E. TRAPHAGEN, OF BROOKLYN, NEW YORK.

SHOE-LACE.

1,373,687.

Specification of Letters Patent.

Patented Apr. 5, 1921.

Application filed February 9, 1920. Serial No. 357,245.

To all whom it may concern:

Be it known that I, MAXWELL E. TRAPHAGEN, a citizen of the United States, and a resident of Brooklyn, in the county of 5 Kings and State of New York, have invented certain new and useful Improvements in Shoe-Laces, of which the following is a specification.

This invention has as one of its objects to 10 provide a lacing having tips comprised principally of textile fabric so combined with the lace as to be inseparable.

A further object is to provide a tip of 15 essentially integral construction with the lace, capable of being colored to match, presenting a neat and attractive appearance, and which is adapted for long continued service and can be manufactured at a minimum of cost.

20 A further object is to provide a lace tip made by wrapping a thread tightly about the extending end of the tape in such a manner that if any part of the winding be severed, the remaining sections will not unravel.

25 These objects are attained by the novel construction, combination of parts and use of materials hereinafter set forth and shown in the accompanying drawings, forming a 30 material part of this disclosure, and in which:—

Figure 1 is a fragmentary view showing a conventional type of shoe lace and indicating the initial operation of formation.

35 Fig. 2 is a similar view of the same showing the final stage of construction.

Fig. 3 is a fragmentary view of the thread or cord used in winding the tip, drawn to an enlarged scale and showing the protective covering.

40 Fig. 4 is a diagrammatic view showing a modified form of winding the tip.

Referring to the drawings in detail, the 45 numeral 10 designates a common form of shoe lacing, which obviously may be of any desired length and made of any preferred material, as silk, linen, or cotton, either plain or mercerized, the several fiber strands being woven or braided into a relatively 50 narrow flat strip or tape as indicated.

This tape, after being cut to length, has 55 passed through it, adjacent the ends, a plurality of stitches 11, a strong thread 12 being used, previously coated with shellac, wax, or the like as at 14, one end of which is thus firmly secured in the tape while the

free end is tightly and smoothly wound about the extending end of the tape, which is compactly gathered into cylindrical shape for that purpose and is of a suitable length 60 to form the tip.

The convolutions of the coil 15 are juxtaposed circumjacent to the gathered end of the tip by suitable mechanism, and the free end of the innermost coil passed repeatedly 65 through the tape as at 16, thereby preventing unwinding of the coil and also acting as a securing means for the thread 12 as well as a reinforcement for the end of the tip.

Finally the tip may be dipped or otherwise coated with shellac or similar quick 70 drying material, when in liquid or semi-liquid plastic state, which impregnates the coil, filling the interstices and providing a relatively hard, smooth, glossy and imper- 75

vious surface constituting a casing or covering which stiffens the tip to the necessary degree.

While the foregoing description refers to

a lace made of tape, it will be apparent

80

that tubular or other form of lacing may

be utilized as the body and treated in a

similar manner.

It will be understood that the thread 85 used agrees in color with the lace and that the shellac may have incorporated in it suitable colored pigments, so that a uniform appearance of lasting quality is obtained.

In the modified form of winding, shown 90 specifically in Fig. 4, the body 20 of the lacing material is gathered at the end 21, and at the extremity of the tip is secured the bight of a similar thread, the diverging 95 ends 22 and 22' being wound in reverse manner, forming alternate coils 23 and 23', crossing at their intersections, forming an 100 interlaced structure in which each coil is constrained tightly and securely upon the gathered tip, the thread ends 22 and 22' ultimately being engaged in the manner before described with the body of the lacing.

Thus the structure of the tip is homogeneous and non-separable, even under the most severe conditions of use, and no metal or other material subject to corrosion or loos- 105 ening is employed.

From the foregoing it will be seen that 110 lacings for such common purposes as shoes, corsets, etc., may be provided with an effective and substantial form of tip capable of being threaded through eyelets and like openings in an easy and convenient manner.

Having thus described my invention and set forth the manner of its construction and use, what I claim as new and desire to secure by Letters Patent, is:—

- 5 1. A lace comprising a body portion, a flexible strand stitched securely into said body portion and coiled tightly over the end portion thereof including the stitches, said strand being stitched into the body beyond the inner end of the coil thus formed.
- 10 2. A lace comprising a body portion, flexible strands stitched securely into the ends of

said body portion from its extremities inward toward its center and then outward to the extreme ends, tightly wound over 15 the end portions thereof the length of the coils being sufficient to form tips, the ends of the strands being repeatedly passed through the body, in the manner of stitching, adjacent the inner ends of the coils 20 formed by the windings.

In testimony whereof I have signed my name to this specification.

MAXWELL E. TRAPHAGEN.
